UNITED STATES PATENT OFFICE.

JOSEPH W. FROST, OF WASHINGTON, DISTRICT OF COLUMBIA.

ELECTRICAL TRANSMITTING DEVICE AND CIRCUITS THEREFOR.

1,195,574.

Specification of Letters Patent. Patented Aug. 22, 1916.

Application filed July 13, 1911. Serial No. 638,820.

To all whom it may concern:

Be it known that I, JOSEPH W. FROST, a citizen of the United States, residing at Washington, in the District of Columbia, have invented certain new and useful Improvements in Electrical Transmitting Devices and Circuits Therefor, of which the following is a specification.

This invention is an improvement in automatic fire-alarm telegraph systems and in a combined transmitting and annunciating mechanism; including circuits therefor. In Patent Number 563,474 dated July 7th, 1896, and issued to myself, a somewhat similar system is shown, but the mechanism to be described, with its circuits and connections, is more efficient and economical than that of the patent referred to. Because of advantages described in said patent, an open-circuit thermostat, having multiple contact points, is combined with a closed-circuit system; thus securing the advantages of each form without the disadvantages of either. A disk form of thermostat is shown in the patent referred to and is preferred; but it is plain any other form having similar multi-contact points may be used.

The invention is illustrated in the accompanying drawings in which,

Figure 1 is a front elevation of the transmitting and annunciating mechanism, showing the relative position of the parts as used in practice. Fig. 2 is a side elevation of same with magnet coils removed. Fig. 3 is a horizontal section on the line α α of Fig. 2. Fig. 4 is a sectional view on the line y y of Fig. 2. Fig. 5 is a diagram of the circuit in its normal condition. Fig. 6 is a diagram of the circuit in a working position. Fig. 7 is a side elevation of the main line cut-out switch. Fig. 8 is a face view of the annunciator dial and its pointer, which is carried by the main shaft of the mechanism. Fig. 9 is a detail perspective view of the step contact stop. Fig. 10 is a detail of the main line "make and break" mechanism; and Figs. 11, 12 and 14 are side views of each one of the three pairs of transmitting disks. Fig. 13 is a side-view of the normal position of spring contact 88 and cylinder contact plate 226 more fully hereinafter described.

The function of the mechanism to be described, as shown in the patent referred to, is to transmit from a local to a central point, certain classes of signals, and to annunciate locally, the information so transmitted. For

instance, if the mechanism transmits to a central point, by means of a distinctive number, the information that a fire exists in a building indicated by such number, and also by an additional signal the particular part of the premises affected, it will also locally announce by means of a dial plate and a pointer attached to said mechanism, the same information for the benefit of those who may be already upon the scene.

Referring to Fig. 1: here is shown a special clock work 20, with a train of gear wheels 21, and pendulum 22, regulating the speed thereof, the coiled spring motor 23, the detent armature 24, operated by the electromagnet 25, and which is practically similar in all essentials to the ordinary form of "trip" mechanism used in automatic fire and burglar alarm systems. The system being a "closed-circuit" one, the armature 24 is normally held to the magnet cores, and the detent lever 26 is therefore, in engagement with the end of pendulum 22, thus holding the entire mechanism in check. In the patent referred to a single transmitting wheel is shown, which is of considerable diameter, and on the periphery of which three classes of signals are cut, viz: 3 cuts to indicate some derangement in the circuit; 3 (repeated) to indicate a fire signal, and single cuts or notches to indicate the sections. This large wheel revolves but once and its shaft carries a pointer which, in connection with a dial, necessarily indicates locally the information transmitted. In the present improvement, this large unwieldy wheel is replaced by 3 very much smaller disks, which revolve a greater number of times; and 3 additional signal disks for the purpose to be described. These 6 disks are shown as a group in Fig. 1 by number 27. By 28 is shown a magnet and its armature 29, which is normally retracted so as to close the contacts 30 and 31, the province of which will be indicated later.

The main shaft of the clock movement 31, besides carrying the regular gear wheel 32, by which a typical train of gear wheels, with its pendulum, is driven, carries the gear wheel (not shown in Fig. 4) 33; this engages with gear wheel 34 of the same diameter and number of teeth. In turn, 34 engages with pinion or cog-wheel 35, which is suitably fastened to the shaft 36, carrying the six transmitting disks referred to. As pinion 35 has but one third of the number

2

of teeth as cog-wheel 34 which actuates it, the break wheel shaft is carried three revolutions while the main shaft 31 of the clock movement is carried but one. This main shaft projects through the frame-work of the clock movement 37, and carries, on the upper side of said framework, a cog-wheel 38; this is of the same size as 39 which revolves on a short shaft journaled to the framework and which is long enough to support beveled-gear wheel 40, fully shown in Fig. 2. This beveled-gear wheel engages with one of equal size (41—Fig. 2), which is attached to a shaft 42, (Fig. 2), the said shaft being supported by a bearing 43, and a casing fastened to the clock work frame as shown in both Figs. 1 and 2. To the beveled gear shaft is attached the index pointer 43, which is carried by it. It is evident therefore that said index pointer revolves once to one revolution of the main shaft.

To the main shaft and just above the wheel 38, is fastened a cog-wheel 44, which engages with a gear wheel 45, having one half the number of teeth as its driver 44, so that said wheel 45, revolves twice while the wheel 44 revolves once. Wheel 45 carries a short cylinder shaft 46, which carries a cog-wheel 47, of the same size as wheel 48, with which it is in engagement. A short extension of this shaft 46, is driven tightly into a rubber or wooden cylinder 49. It will be understood the shaft 46 is journaled to the framework 37, of the clock movement. At the other end of the cylinder 49, is driven a short shaft 50. The cog-wheel 48 driven as described by 47, carries a similar cylinder, its shaft 51, also being journaled to the framework 37, and the cylinder also having at its other end a similar short shaft 52 driven into it. The shafts carrying these two cylinders being journaled as described at one end, are supported at the opposite ends by 53, which is bolted to the support 54, said support being threaded at its opposite end and screwed into the framework.

Referring to the gear wheel 34, the same is fastened to a shaft 57, which extends upward and loosely through the framework. This shaft is journaled to and supported by 56 which is suitably attached to the framework 37. To the upper end of this shaft is attached a two-step stop (57'), by means of an inner hub (Fig. 9), and a set screw 59. It is deemed sufficient to describe the two lower cylinders 60 and 61, their shafts, frames, &c., by stating they are connected to the mechanism in identically the same way as those above described; the wheel 62 performing the same function as above described gear wheel 44, and the wheel 63 as that of the above described gear wheel 39.

As far as the mechanism has now been described, it is seen that while the main shaft 65 of the clock work is revolving once, the

index pointer 43, and the two step stop revolve once; and that the 4 cylinders 49, 49', 60 and 61, revolve twice, while the signal disks 27, revolve three times. A reference to gear wheels 62 and 63 will show that while 63 with its corresponding wheel 45, has its teeth intact, the main shaft wheel 62 and its corresponding wheel 44, have certain parts of their teeth cut away; so that the action of cylinders 49 and 49' and that of 60 and 61 is intermittent. These wheels are however normally in engagement.

In connection with the signal disks 27, are contact pieces 64 and 65, the upper ends only being shown in Fig. 1; while Fig. 10 shows the details thereof. These two spring contacts are suitably fastened to the insulating lug 66, which is in turn fastened to the metallic base and weight 67. This base with its insulated holder and its contact pieces 64 and 65, drops by gravity to two different positions other than its normal (as shown on Fig. 1), as the clock work progresses. The necessity of its being of sufficient weight is therefore apparent. The base 67, has running through it, under the shaft 36 (which conceals part of same in the drawing), the shaft or rod 68 to which it (67), is securely fastened. This rod slides through the frame of the clock work in holes slightly larger than itself so as to allow free movement thereof. From the upper end of this rod, to which it is fastened, and extending at right angles to same, is a lever 69, the free end of which rests on the upper edge of the contact step stop 57'. The normal position of the free end (the step stop turning in the direction of the arrow when the clock movement is active), of lever 69 would be at the point indicated by 70.

Arranged along the sides of the four cylinders 49, 49', 60 and 61, are a series of spring contacts, the top ends of which are shown in Fig. 1. A side view of part of same is shown in Fig. 2; in Fig. 3 is shown the manner in which they connect with the cylinders and in which they are fastened to the base of the whole mechanism, which base is of an insulating material. Of these contact springs there are 8 on each of the two upper cylinders, and 10 on each of the two lower ones. The lower ones are sectionizing cylinders, and the number of springs connected therewith determine the capacity of the box for sectionizing. Thus the ten pairs of springs would sectionize for eight sections; the two lower springs on opposite sides and the two upper ones being necessary to connect the sectionizing springs proper to the rest of the circuit.

Referring to Fig. 5: this is a diagram of the circuit when in its normal condition. It will be understood that each of these boxes and the building it protects, is operated by a local battery, the signal to the central

point being relayed by the signal disks and their spring contacts in a well known manner. The circuit is as follows: Starting from one pole of the battery 71, the main closed circuit runs by wire 72 to cylinder contact spring 73, cylinder bridge 74, spring 75, to wires 76 and 77; these wires 76 and 77 running continuously through a building back to spring 78, bridge 79, spring 80 and wires 81 and 82, also running continuously through the building, back to spring 83 bridge 84 spring 85, wire 86 to trip magnet coil 25, wire 87, spring 88, wire 89, to the first of lower set of springs 90, bridge 91, spring 92 loop 93 (constituting the first section into which a building may be divided), spring 94, bridge 95, spring 96, loop 97 (constituting a second section), spring 98, bridge 99, spring 100, loop 101 (third section), and so on to spring 102, wire 103, to relay magnet coil 28, to spring 104, bridge 105, spring 106, to ground 107, to ground 108, spring 109, bridge 110, spring 111 to contact spring 64, wire 112 through relay armature contacts 113, wire 114, spring 115, bridge 116, spring 117, wire 118, to battery. Two open arms run from each pole of battery viz: 119 and 120, respectively to springs 121 and 122. Their purpose will be hereafter described. From this description of the circuit it will be seen that with the exception of the two short wires last referred to, every vital contact spring and magnet wire in the box, and all wires running through the protected building, has a current normally flowing through them, and this current also flowing through the magnet coils 25, its armature 24 holds the mechanism in check, the dial pointer 43, (Fig. 8), pointing to the indication "O. K." on the dial. At this time all the cylinder contact springs, are connected in series by bridges as shown in Fig. 5, and in detail by cylinder 49 of Fig. 1. It is necessary, in order to "set" the box to normal, to push the armature of relay magnet 28 to its contact 30 inasmuch, as shown in Fig. 5 at 113, those contacts form part of the circuit. In practice the trip and relay armature are arranged as shown in Fig. 1, gravity being used for retraction.

In order to describe the partial operation of the mechanism at this point, such as would be caused by any derangement of the circuit other than that caused by the normal operation of a thermostat; the transmitting disk 27 may be described in more detail. The province of these disks, as shown, is to transmit in a well known manner, the different classes of signals to a central point. They are divided in groups of two, there being three of these groups, or 6 disks in all. Each of a pair contain such notches or cuts as are necessary to transmit the same signal in different forms. Referring to Fig. 1,

contact spring 65 is normally in contact with disk 202 (Fig. 11), and contact spring 64 is normally out of contact with wheel 201—see also Fig. 11. These transmitting disks, in connection with their contact springs, transmit, in the course of their revolution, what may be designated "derangement" signals, as well as fire signals; one of them (202) with its contact alternately opening and closing the circuit, and thereby operating the signal 216 by means of battery 217; and the other 201, in conjunction with its contact, alternately throwing a ground on and off the main line; the contact spring 64, being grounded as shown in Fig. 5, (108), and the disk being also connected with a main line containing the signal 211, the battery 212, and ground 214. These two are typical main line transmitting circuits, commonly known as "closed" and "open" circuits. The derangements which will be indicated by the contact wheels 201 and 202 are: first, a break in the local circuit; second, a breaking of the local battery 71, which is practically the same thing; third, the grounding of the local circuit; and fourth, the crossing of a local section wire (as 101 loop Fig. 5), with a continuous wire, as 76, 77 Fig. 5, or 81—82 Fig. 5. As will be shown, the crossing of a section wire with both of the continuous wires, at or about the same time, which condition arises from the normal action of the thermostat 225 (Fig. 5), will cause the mechanism to give the fire alarm, by revolving the signal wheels shaft at least twice and as much farther as the particular section affected admits.

In the case of a break of a wire say at a 3rd section Fig. 5, the clock works starts by the retraction of the armature 24 by gravity, and the release of the pendulum 22 by the detent 26, (Fig. 1). The group of signal wheels 27, revolve in the direction of the arrow (from left to right), and the mechanism is stopped only after the signal 27 (see 201 and 202), is transmitted over their respective circuits as shown; because by the operation of the cylinders, (all four of which are thrown out of normal on the first movement of the clock work), the circuit is changed so that the current will again flow through magnet coils 25, attract the trip armature to its magnet, and check the clock work at such a point as will permit only the signal 27 to be transmitted. The circuit thus restored through the trip magnet coils is as follows: from battery 71 (see Fig. 6), wires 119 and 72, to cylinder contact plate 226 and through said plate to spring 85, wire 86, through magnet coils 25, wire 87, wire 89 to and through spring 90 (Fig. 6), cylinder contact plate 215 to lower spring 90' wire 91', spring 92', cylinder plate 216, and along said plate to upper spring 102, 125

and from thence through wire 103, coil 28, spring 122, plate 227, spring 117 to battery by wires 120 and 118; thus short-circuiting all the section wires as well as the two continuous wires which constitute practically all the wires running through the building protected. In the event of a grounding of either one of the continuous or section wires, the same signal would be transmitted, 10 although the cause of the starting of the mechanism in the case of a ground on either continuous wire, would be a different one than that which would cause the mechanism to start if a section wire were grounded. 15 Should a ground occur on the continuous wire 76—77 say at t , the coils of trip magnet 25 would be shunted out as follows: battery 71 (Fig. 5), wire 118, wire 120, spring 117, bridge 116, spring 115 to ground 20 108, to trouble ground at t , wire 76, spring 75, bridge 74, spring 73 and wire 72 to opposite pole of battery. This shunt would cause the mechanism to start and continue until said shunt was removed. In the case 25 of a break, as shown, the circuit is restored and the mechanism stopped as described. In the event of a short-circuiting or shunting as just explained, the mechanism is stopped by the throwing off of the normal 30 or detecting ground, by the operation of the cylinder 49' and its contact plate 230, Fig. 1. After this cylinder moves as described, in the direction of the arrow, on the starting of the mechanism, and as shown at Fig. 35 5, the two springs 106 and 109 connected to grounds 107 and 108, are, together with springs 111 and 115 cut entirely away from the rest of the circuit, and all of them rest on the cylinder contact plate 230, as shown 40 at Figs. 1 and 6. The detecting ground or grounds which are part of the shunt, being thus disconnected from the circuit, the current is restored through the trip coils, and the signal disks 201, and 202 are stopped at 45 a particular point in their revolution, so as to transmit the "attention" or trouble signal referred to. Referring to Fig. 11, which shows the two signal disks involved thus far, the letters *f. f.* indicate about the 50 location on the disks where the points of the contact springs 64 and 65 rest, when the mechanism is at its normal position. That part of the disks marked *g. g.* indicate the location of the contact springs 55 after an "attention" signal, such as has been described (viz., a break of the circuit, or a grounding of same), is transmitted. As it is essential that the disks, in case of such troubles, and the pointer 43 of dial shown 60 by Fig. 8, and which follows the mechanism, should stop at about the same place; and further, in order to prevent the stopping of the mechanism before it has sent in a complete trouble signal (as by a temporary break or ground), provision now to be

described has been made: it will be seen that contact spring 88 (Figs. 1, 5 and 15), is normally resting on the insulated portion of cylinder 226. As shown by Fig. 5, this spring is one side and constitutes part of 70 an open shunt around the trip coil 25, while spring 85 immediately adjoining it, is connected to the other side of said trip coil. It is evident that the bridging of these two springs will shunt the trip coils and keep 75 the mechanism in operation after the same is started by the causes above enumerated. As will be seen from Fig. 15, just after the movement is started, the contact plate 226 cut away so as to normally disconnect 80 spring 88 from the circuit, comes in contact with said spring, thus connecting springs 85 and 88, bridging the trip coils and causing the clock work and with it the disks 201 and 202, to run until the points of 85 their contact springs are opposite the location on the disks indicated by *g. g.* At that time the shunt, of which spring 88 is a part, is broken, because of the disconnection of said spring from the circuit by 90 means of the break in the contact plate 226, Fig. 13.

If a section wire should be grounded the relay coils would be shunted by means of a bridge or shunt formed from the detecting 95 ground 108 to the "trouble" ground. The shunting of these coils 28 (Fig. 5), would cause the armature and its contact at 113, to break the whole local circuit and the subsequent action of the mechanism would be 100 exactly the same as in the event of a break in any other part of the circuit. It is plain that the action of the mechanism in thus transmitting a trouble signal would be followed by the pointer 43, which would be 105 carried by means of the described beveled gear, to within the division of the dial marked "Attention." (See Fig. 8). There are two other kinds of "trouble" signals, one of which is of great importance, as it 110 quite likely would be caused by the partial operation of a thermostat and would indicate an undue or dangerous temperature or a cross between a section wire and one of the 115 continuous wires. A reference to Patent 563,475 dated July 7, 1896, and issued to myself, shows in detail the thermostat which is preferably used in connection here-with. This thermostat has two contact screws (as shown here by Fig. 5), one of 120 which 240, is shown as being farther from the thermostatic disk than the other 241; the latter being adjusted relative to the disk so as to come into contact with it, say at 130 degrees of temperature, while the former 125 would be adjusted to come into contact with the disk at say 150 degrees. In the event of the temperature rising to the lower point (130 degrees), from a cause other than that 130 of an actual conflagration, it would be im-

portant that information of such fact be transmitted to the central point for appropriate action. A distinctive signal of this or its equivalent an accidental cross between the wires, is very simply given as follows: The thermal disk 225, coming into contact with the contact screw 241, would bridge or shunt out the trip magnet coils (see Fig. 5), by the following circuit around said coils: from battery 71, wire 72, spring 73, bridge 74, spring 75, wires 76 and 77, spring 78, bridge 79, spring 80, wire 81, through screw 241 to disk 225, to and through section spring 100, around as shown in the description of the circuit first given, to the opposite pole of the battery. This shunt would cause the mechanism to run until the points of contact springs 64 and 65, Fig. 11, were each opposite the point of the disks marked *h. h.* respectively. Not only, then, would the signal 72 be transmitted but an additional impulse over the main line be given by the lug *i* on disk 201, and the notch *i'* on disk 202. This would indicate at central office that either there was a cross of the wires in the building protected, or an undue heat which should be promptly attended to. The reason of the stopping of the mechanism at this point is as follows: The shunt or cause of the mechanism's release is removed by disconnecting either the section springs (Fig. 5), from the circuit, or the continuous wire springs 80 and 83. As the cylinders and their contact plates controlling the section springs, do not come into action until a later period, the springs 80 and 83 must be automatically disconnected in order to stop the mechanism. Referring to Fig. 6, it will be seen that at two certain points (242 and 243), in the contact plate 226, covering the cylinder, the said plate is cut away, leaving those portions of the cylinders insulated; so that when the cylinder moves far enough the continuous wire terminal springs 80 and 83, are disconnected from the circuit, and the shunt is broken. Similarly if a cross should occur between a section wire and the other continuous wire the action would be practically the same, except that two instead of one impulse would follow the signal.

It may be remarked that the "low" point of the thermostat is always connected with the same continuous wire (that wire the terminals of which are disconnected first), and the "high" point with the other continuous wire. If the continuous wire connected with the "high" side of a thermostat, should cross with a section wire, a practically similar shunt, starting the mechanism, would be destroyed after the same should run somewhat farther and so as to cause another indication to be transmitted by the lug *e* on disk 201, and the notch *e* on disk 202. If that were the case, the second cut *e* of disk 202 (Fig. 11), would allow 67 (Fig. 1), with

the 2 contact springs 64 and 65, to drop to the second pair of signal disks, because at that point the shaft 68 and its lever 69 would drop off, by gravity from the first step of the device 70; and the contact springs fixed to same would be ready to act in conjunction with disks 203 and 204, Fig. 12. The use of the cut *e* to allow of the drop and at the same time act as a part of the signal transmitter, is considered an important practical feature of the contrivance. After the drop is made as described, the two contact springs rest about in the position marked *k. k.* on the two disks 203 and 204.

There has now been described the manner of transmitting the class of signals designated "derangement" or "trouble" signals and the manner in which the same have been locally indicated by the pointer and dial; it being understood that the extent of the revolution of the transmitting disks determines the class of signal transmitted, and that, as the pointer follows these movements, its position will indicate the same information as is transmitted, the dial being suitably marked as shown.

Before describing the operation of the machinery in the transmission of a fire alarm, the movement of the four cylinders and their contacts plates, and springs which act to check the mechanism, will be referred to more in detail. As an examination will disclose, these cylinders turn in the direction of the arrows, or each pair toward one another. On the first movement of the clock work, the two upper cylinders are turned so that their contact springs are all disconnected from their series bridges (see Figs. 1 and 5), and thrown into connection with one another by the contact plates 226 in the case of cylinder 49. The contact springs of cylinder 49' are disconnected similarly and thrown into electrical contact in groups, as shown in Fig. 1. This figure shows the cylinder 49 in its normal position, while the cylinder 49' is shown in a working position with spring 111, shown out of contact from reasons described later. These two cylinders, after the starting of the clock work, continue their revolution until the trouble signals described, a break, ground, or a single cross are indicated. In the event of the double "cross" signals described, they finish their revolution and are then at rest. The driving cog-wheel 38, connected to the main shaft as described, has nine of its sixteen teeth cut away so that, as the wheel 45 it engages with has 8 teeth, the cylinders will make nearly a full turn before they accomplish their full purpose and come to rest.

Referring to the two lower (or section) cylinders 60 and 61 (Fig. 1): these are normally shown with section terminal springs of the first, second, third, fourth, fifth and sixth sections disconnected; which would be

their position after a fire signal coming from the sixth section of a building had been transmitted. The normal position of the springs is shown in Fig. 5 as being in series 5 through the bridges 91, 95, 99, and so forth. As in the case of the two upper cylinders (Fig. 1), on the first movement of the mechanism from any cause these cylinders are turned toward one another and all of their 10 springs electrically connected, there to remain until the proper time, when the two terminal springs of each section are successively disconnected by means of the steps *l, m, n, p, q, r*, the other two steps on cylinder 15 61 not being shown. The cog-wheel 62, connected to main shaft and actuating 63, has its teeth cut away to the extent of one half, so that these lower cylinders also revolve only once. It will be seen by reference 20 to these wheels (62, 63) that the teeth are barely in engagement and that a small movement of the clock work, and consequently the cylinders, is made before the same, by reason of the cut away teeth, are out of gear. 25 Such number of teeth are cut away from 62 that the cylinders are inactive after their first movement, and until called upon for further service, which is after the second or fire number (which designates the building 30 affected), is transmitted, and it becomes necessary to transmit the signal showing in what section of the building the fire is located.

From the above description given as to 35 the effect of the crossing of a section wire with either of the continuous wires, and the resultant stopping of the mechanism, by the automatic breaking of the shunt, it will be seen that if both continuous wires be crossed 40 at or about the same time the clock movement would not stop running as before indicated, because at all times there would be a shunt of which at least one of these continuous wires would constitute part of such 45 shunt; so that the movement, continuing on, would cause disks 203 and 204 (Fig. 12), to transmit their signals (334), to the central point, the said signal being the fire signal such as would be caused by the complete 50 action of a thermostat, viz: the contact of both contact screws (241 and 240, Fig. 5), with the disk 225 connected to a section wire as shown. As an operated thermostat must be connected to one of the section 55 wires, the fire signal would be transmitted, followed by a certain number of impulses to indicate the floor or section. Disks 203 and 204 not only transmit the fire signal but one and part of another (first and second), of the section signals by means of the lug 250 on 203, (Fig. 12), and cut 251 on 204; and if the mechanism was checked at a point to indicate the first section the contact spring would rest at the point 60 marked *y. y.* on these disks. The movement 65

would be checked at this point because at that time the step off or section cylinders (Fig. 1), would have started by means of gear wheel 62 engaging with the wheel 63, and progressed far enough for the step 1 70 to have disconnected springs 2' and 3' from the circuit; thus destroying the shunt. In the event section 2 should operate, or following sections, the contact springs of disks 203 and 204 would be permitted to drop, as 75 before described, through the second section cut *w.* of disk 204, to the third pair of signal disks 205 and 206, which as before described are section indicating disks. The operation of the system in the event of the full 80 operation of a thermostat on any other section would be the same. On wheels 205 and 206, after the 8th section indication marked *a. a.*, are two more notches and cuts respectively. If the two short wires leading from the battery 71 (Fig. 5), 72 and 118 should break between the battery and the mechanism, the two extra wires 120' and 119, would be joined to the circuit just after the starting of movement, (Fig. 6) and thus the 90 efficiency of the system as affected by such condition would be preserved. If, however, the battery itself should be disconnected, the whole mechanism would run down and in addition to all the signals referred to, two 95 additional impulses, indicating this, would be transmitted by the two additional notches and cuts just referred to. It will be borne in mind that the pointer 43 (Fig. 8), would as shown indicate the section number in case 100 of fire, as well as any other signal transmitted.

In Patent Number 563,586, dated July 7th, 1896, issued to myself, there is shown an automatic repeating device. The lug *z* 105 shown on signal disk wheel 203, is the lug equivalent to the prolonged ground contact *c* of that patent. As is disclosed therein this ground lug permits the grounding of the main line circuit for a comparatively 110 prolonged period, long enough for the mechanism to "cut in" a repeater circuit connected with a third station, such as municipal fire-alarm headquarters; so that the fire signal only may be repeated on, in order 115 that a "battery" signal such as has been described and which causes the whole mechanism to run down, may not cause the fire signal 334, to be repeated to the third station, provision herein shown will be described for suppressing this prolonged ground in the event of such a (battery) signal. By reference to Fig. 1, it will be seen that springs 106, 109, 111 and 115 are connected together after the starting of the box, 120 and by reference to Fig. 5, it will be seen that 111 and 115 are both connected to contact spring 64, 111 direct, and 115 through the armature contact of magnet coil 28. These two springs, 111 and 115, are also 125 130

connected to the two grounds 107 and 108 by means of the springs 106 and 109, and the plate 260₁, and are isolated from the local circuit after the starting of the movement, so that the spring 64, is grounded from two sources, the armature contact 113 being intact. If however, the battery fails this contact 113 is broken, and the spring 64 is grounded, only through the spring 111. By reference to Fig. 1 it will be seen this spring is out of contact with its plate. This is to illustrate the condition produced as shown in Fig. 6, by the cut away portion 229 of the plate 227 when the electrical contact between said plate and spring is broken. When the lug 2, Fig. 12, is in contact with the spring 64, the spring 111 is passing over the insulated portion of the cylinder 229, and out of contact with the ground; so that both grounds being destroyed, in the event of a battery signal the same is not permitted to be repeated from the central point.

Referring to Figs. 11, 12 and 14, it will be seen that they show three pairs of transmitting disks to wit 201 and 202, 203 and 204, and 205 and 206; 201 and 202 being shown in an open grounded circuit and 203 and 204, in a closed metallic circuit. Each pair transmits the same signal and are for the purpose only of transmitting the signals in duplicate. By providing for a plurality of small disks and causing them to revolve more than once in the manner shown, a longer signal may be given and without additional contact springs one of which only need be employed, and which is made to shift from one disk to another so as not to disturb the continuity of the signal. It will be also noted that either the contact spring may shift relative to the disks and at right angles to the direction of their movement (as shown), or the springs may be fixed and the disks likewise shifted, without departing from the spirit of the invention.

The claims are:

1. In an electrical distinctive signal transmitting device, a motor driven clock mechanism, an electro-magnetic actuating or releasing device therefor, a shaft of said clock mechanism carrying a series of distinctive signal transmitting disks connected with one pole of a current generator and fixed to their shaft, selectively shifting contact points coöperating with the disks and connected with the opposite pole of the generator, and circuit controllers (such as thermostats), in circuit with the said actuating or releasing device, substantially as described.
2. A motor driven mechanism including an electrical signaling device, an electro-magnetic controller therefor, a normally closed circuit through the said magnet including a battery, a series of loops on either side between the battery and the magnetic controller, spring contact terminals normally in circuit with said battery and said loops, switch contact bridges normally connecting said terminals and loops in series with said battery, and normally open switch bridges for directly connecting the said spring terminals, substantially as described.
3. A motor driven mechanism including an electrical signaling device, an electro-magnetic controller therefor, a normally closed circuit through the said magnetic controller including a battery, a series of loops on either side between the battery and the magnetic controller, spring contact terminals normally in circuit with said battery and loops, switch contact bridges normally connecting said terminals and loops and in series with the battery, normally open switch bridges for directly connecting the said spring terminals, and a resistance coil constituting an electromagnet between the battery and the series of loops on one side of the battery, substantially as described.
4. In an electrical signal transmitting device two or more notched disks fixed to a clock-work shaft making more than one revolution to complete a definite signal said disks connected to one pole of a current generator, a spring contact coöperating therewith connected to the opposite pole of the generator and arranged to mechanically shift from one disk to another and at right angles to the direction of movement of the disks; a suitable releasing device for starting the clock-mechanism, and apparatus at a distant station for receiving the signals therefrom, substantially as described.
5. In an electrical signal transmitting device two or more notched disks fixed to a clock-work mechanism shaft making more than one revolution to complete a definite signal said disks connected to one pole of a current generator, a spring contact coöperating therewith connected to the opposite pole of the generator and arranged to mechanically shift from one disk to another and at right angles to the direction of movement of the disks, an electro-magnetic releasing device for starting the clock mechanism and in circuit with switches (such as thermostats) located at a second station, and apparatus at a distant station for receiving the signals from the said disks and the contact spring, substantially as described.
6. In an electrical signal transmitting device two or more notched disks fixed to a clock-work mechanism shaft making more than one revolution to complete a definite signal, the said disks being notched to transmit a series of distinctive signals and connected to one pole of a current generator; a spring contact coöperating therewith connected to the opposite pole of the generator and arranged to mechanically shift from one disk to another and at right angles to

the direction of movement of the disks; an electromagnetic actuating device for starting the clock-mechanism and in circuit with circuit controllers (such as thermostats) located at a second station, an index pointer attached to the main shaft of the clock-mechanism, a dial the face of which is traversed by said pointer, and apparatus at a

distant station for receiving the said distinctive signals, substantially as described. 10

In testimony whereof I have affixed my signature in presence of two witnesses.

JOSEPH W. FROST.
